ENVELOPE FOR ELECTRIC DEVICES

Albert Koerbis, Irvington, N. J., assignor to
 Hanovia Chemical & Manufacturing Company,
 Newark, N. J., a corporation of New Jersey

Application December 14, 1950, Serial No. 200,729

4 Claims. (Cl. 313—182)

1

This invention relates to the sealing of conductors into or through envelopes of vitreous material and is concerned in particular with producing a hermetically sealed envelope having electric lead-in conductors but no seal-off tip.

In the manufacture of electrical devices, such as, for example, vapor electric discharge devices having envelopes of vitreous material, it is customary to exhaust the envelope and fill it with a gas through a small tube in the wall thereof. After exhausting and, when desired, filling with a gas, the tube is sealed off by forming a tip that protrudes from the envelope. A protruding seal-off tip on the wall of an envelope is, of course, troublesome since it is susceptible to being broken off easily. To avoid this likelihood of damage to the envelope, seal-off tips have often been formed in an end of the envelope, usually near the lead-in conductor seal; however, even when so located, a seal-off tip is objectionable and special caps or bases must be provided to cover it.

Besides being liable to easy breaking off when not handled carefully, a seal-off tip on an envelope that becomes heated during operation is somewhat cooled by the surrounding air, whereupon it may crack or fracture the envelope due to unequal strains in the vitreous material that forms the envelope and the seal-off tip. Furthermore, in the case of, for example, metal vapor discharge lamps, cooling of the seal-off tip causes the metal vapors to condense in the tip which adversely affects the operation of the lamp. To correct for the cooling of the seal-off tip, arrangements have been proposed for locating the seal-off tip where it may be heated by connection currents, but expedients of this type involve many complications and are not entirely satisfactory.

It is accordingly an object of this invention to avoid the above noted difficulties and to provide an envelope for an electric device with no seal-off tip either in the wall or an end thereof. Further objects and various advantages of the invention will appear as the following description proceeds and by reference to the accompanying drawing in which Figures 1, 2, and 3 are sectional views of an end portion of an envelope for a vapor electric discharge device and show the several steps involved in practicing the method of forming a hermetically sealed envelope according to the invention.

For the purpose of illustration, I have chosen to describe the details of my invention by reference to a vapor electric discharge device of the type wherein a lead-in conductor is sealed in the

2

envelope thereof by forming a bead of vitreous material around the conductor and sealing the bead into an opening in the end of the envelope. I desire to have it understood, however, that this illustration is not limitative or restrictive even of the vapor electric discharge devices contemplated by this invention. The seal between the lead-in conductor and the envelope may be formed directly without the use of a bead, and the lead-in conductor may include a thin-foil portion of molybdenum or tungsten and the like for purposes well known to those skilled in the art.

The envelope of the illustrated vapor discharge device is indicated at 1, and it may be formed of quartz or special ultra-violet transmitting glasses especially when the discharge device is designed for emitting ultra-violet radiations. The envelope 1 is provided with a tubular neck portion 2 at a position where it is desired to locate 15 at least one of the lead-in conductors. A lead-in conductor in the form of a wire 3 is shown in the drawing, and two spaced apart portions thereof are sealed in the beads 4 and 5. The beads 4 and 5 may consist of the vitreous material used to 20 form the envelope 1 and the neck portion 2, or they may comprise one or more transition glasses having graded expansion coefficients which lie between the expansion coefficients of quartz, i. e. when the envelope is formed of quartz, and the 25 metal of the lead-in wire 3.

Figure 1 shows an exhausting or filling tube 6 attached to the tubular portion 2 and communicating with the space within the envelope through the opening 7 in the portion 2. After the envelope is closed by forming a temporary outer seal 8 around the bead 4, the envelope is exhausted through the tube 6 and in the case of a mercury vapor discharge device, is filled with a starting gas, such as argon, krypton and zenon, and a 30 small quantity of mercury is passed into the envelope through the tube 6.

After the envelope has been filled as desired, the tube 6 is sealed-off forming a tip, as shown at 9 in Figure 2. No special precautions in forming the tip 9 need be taken, such as maintaining a critical size for the tip as has been required heretofore, since according to the invention the seal-off tip is entirely removed after it has served its purpose. Following this operation of filling 45 and sealing of the envelope, a second or final seal 10 like that shown at 8 is formed around bead 5 by heating and pressing the tubular portion 2 inwardly against the bead 5. Thereafter the tubular portion 2 may be broken off beyond 50 the seal 10 and the lead-in wire 3 may be cut off

leaving a sealed-in conductor in an hermetically sealed envelope with no seal-off tip as shown in Figure 3.

From the above description, it will be seen that I have provided a simple and convenient method for forming an improved hermetically sealed electrical device. No exhaust tip appendage or remnant remains as part of the complete envelope whereby likelihood of damage thereto, through breakage of the tip, is eliminated.

It is understood, of course, that modifications and variations may be resorted to without departing from the spirit and scope of the invention, as those skilled in the art will readily understand. Such variations and modifications are 15 considered to be within the purview and scope of the appended claims.

What I claim is:

1. The method of manufacturing an hermetically sealed envelope of vitreous material for an electrical device comprising the steps of sealing an elongated portion of said envelope around a lead-in wire, providing a tube on said elongated portion, filling said envelope with an ionizable medium through said tube, sealing off said tube, and forming a second seal around said lead-in wire at a location between said tube and the main portion of said envelope.

2. The method of manufacturing an hermetically sealed envelope of vitreous material for an electrical device comprising the steps of positioning a lead-in conductor in a tubular end of said envelope, fusing said tubular end around said conductor, filling said envelope with an ionizable medium through an opening in said tubular end located inwardly of said fused portion, sealing-off said opening, fusing said tubular end around said conductor at a location inwardly of said sealed-off opening, removing that por-

tion of said tubular end that extends beyond the inner seal.

3. The method of manufacturing a vapor discharge device having an envelope of vitreous material comprising the steps of positioning a lead-in conductor in a tubular extension of said envelope, forming a temporary seal between said extension and said conductor, filling said envelope through an opening in said extension arranged inwardly of said temporary seal, sealing off said opening, forming a final seal between said extension and said conductor at a location inwardly of said opening, and removing that portion of said extension that extends beyond said final seal.

4. The method of manufacturing a vapor discharge device having an envelope of quartz, comprising the steps of forming a tubular extension of quartz on said envelope and an exhausting and filling tube on and intermediate the ends of said tubular extension, arranging in said extension a lead-in conductor of a length that is greater than said extension whereby said conductor extends from within the outer end of said extension to within said envelope for carrying an electrode sealing said outer end of said extension around said conductor, exhausting said envelope and said extension through said tube, filling said envelope and said extension with a rare gas and passing a small quantity of vaporizable metal into said envelope through said tube, closing said tube, sealing the inner end of said extension around said conductor, and removing that portion of said extension that extends beyond said last mentioned seal.

ALBERT KOERBIS.
